UNITED STATES PATENT OFFICE.

FRANK CIBOROWSKI, OF WORCESTER, MASSACHUSETTS.

WIRE GUIDE FOR PAPER MACHINES.

Application filed November 21, 1927. Serial No. 234,653.

This invention relates to a device for controlling the travel of a felt belt or wire in the form of an endless apron over a pair of rolls. It is particularly adaptable for use 5 with Fourdrinier wires of paper machines.

The principal object of the invention is to provide automatic means for preventing the wire from running off the roll on which it is mounted. The invention, however, is not 10 confined to its use with Fourdrinier wires or similar wires of paper machines.

Other objects and advantages of the invention will appear hereinafter.

Reference is to be had to the accompanying 15 drawings in which

Fig. 1 is a diagrammatic longitudinal sectional view of a part of a paper machine showing the way in which the press felt is guided therethrough;

Fig. 2 is an end view of the machine, partly in section, showing one end of the guide roll supporting the Fourdrinier wire with a preferred form of this invention applied thereto, and

Fig. 3 is an end view of the same, partly in section.

These wires are quite wide and long and they are supported by rolls which, if made with stationary bearings in all cases, will 30 be apt to result in the running of the wire off of one roll in case there is any slight inaccuracy in the setting up of the machines. This invention is designed to provide automatic means to take care of any travel of the wire along the roll.

In Fig. 1 the machine is shown as having a pair of squeeze rolls 10, through which the felt 11 passes. Supporting rolls 12 carry the felt and a guide roll 13 is shown located 40 in the usual place. This roll is supported in a stationary bearing at one end and an open sided hook bearing 14 at the other end. This latter bearing is supported by a vertical stud 15 having a head under which is a spring 16 for carrying the stud. The tension of the spring is adjusted by a screw 9 carried by a cover 8.

The frame of the machine is provided with a fixed arm 18 on which is pivoted a 50 feeler 19. This feeler is adapted to come into contact with the edge of the felt 11 and is kept in contact with that edge by an operating weight 20 on a bell crank 21 which is connected by a link 22 with the feeler 19. 55 The weight constitutes a non-positive means for normally forcing the feeler 19 against

the felt and also keeping it in contact with its edge. When the felt moves toward the right hand end of the feeler 19, as shown in Fig. 2, it will overcome the action of the weight and move the feeler as indicated in dotted lines. The result of this is to turn the bell crank 21 about its pivot 23, thus raising the weight incidentally and also closing a pair of contacts 24.

This establishes an electric circuit which energizes an electromagnet 25 and pulls down a pivoted lever 26 that is connected with the top of the rod or stud 15. The result is to lower this end of the roll 13 70 which, as the other end is in a stationary or pivoted bearing, will turn this roll on that bearing enough so that the felt will move back. Advantage is taken of the principle that a wire or belt running on a pair of rolls will always move toward the high side. This electro-magnetic means actually moves the roll at one end so that the other side tends to become the high side and the felt moves back. Of course, as soon as it 75 moves back enough to break the contact at 24, that operation stops and the spring 16 raises the bearing 14 again. In this way the action is kept up alternately moving the bearing 14 up and down and preventing the 80 felt from crawling up the roll at either end. This can all be done by action at one end.

This is a comparatively simple device for keeping the felt on the roll. It is operated from one end of the roll and prevents the 90 felt from moving far over to either side. The invention can be applied to any belting proposition in which a belt or other endless apron travels over a pad of rolls, such as a Fourdrinier wire.

Although I have illustrated and described only one form of the invention I am aware of the fact that modifications can be made therein by any person skilled in the art without departing from the scope of the invention as expressed in the claims.

Therefore, I do not wish to be limited in these respects but what I do claim is:

1. In a machine having an endless apron and a roll engaging it, the combination with 105 a movable bearing for the roll, a vertical rod on which the bearing is supported, a spring for holding the bearing up to apply tension to the apron, a magnet adapted to move the bearing down to reduce the tension at that 110 end, a finger positioned to engage the adjacent edge of the apron, and means where-

by, when the finger is moved back toward that end, the magnet will be connected up with a source of power.

2. In a machine having an endless apron and a roll engaging it, the combination with a movable bearing for the roll, a rod on which the bearing is supported, a spring for holding the bearing in a position to apply tension to the apron, a pivoted arm connected with said rod, a magnet in position to swing the arm on its pivot to move the bearing down to reduce the tension at that end, and means whereby, when the apron is moved toward that end, the magnet will be connected up with a source of power.

3. In a machine having an endless apron and a roll engaging it, the combination with a movable bearing for the roll, a vertical rod on which the bearing is supported, a spring for holding the bearing up to apply tension to the apron, means for moving the bearing down to reduce the tension at that end, a finger positioned to engage the adjacent edge of the apron, and means whereby, when the finger is moved back toward that end, said means will be connected with a source of power. 20 25

In testimony whereof I have hereunto affixed my signature.

FRANK CIBOROWSKI.
